[57] CLAIM

The ornamental design for a mud wheel for a tractor, as
shown.

DESCRIPTION

FIG. 1 is a front elevational view of a mud wheel for a
tractor showing my new design;

FIG. 2 is a top plan view thereof, the bottom view being

a mirror image;

FIG. 3 is a rear elevational view thereof; and,

FIG. 4 is a partial sectional view thereof, taken along
lines 4—4 in FIG. 3.

FIG. 1
